UNITED STATES PATENT OFFICE.

DAVID M. BEAIRD, OF COLUMBUS, OHIO.

WRITING-DESK.

1,267,046.

Specification of Letters Patent. Patented May 21, 1918.

Application filed October 28, 1914. Serial No. 869,119.

To all whom it may concern:

Be it known that I, DAVID M. BEAIRD, a citizen of the United States, residing at Columbus, in the county of Franklin and State of Ohio, have invented certain new and useful Improvements in Writing-Desks, of which the following is a specification.

My invention relates to writing desks and is, in nature, an attachment designed to be used in connection with beds of a well known type. My invention is particularly desirable for use among soldiers to be attached to the beds used by them in their barracks.

15 The main object of my invention resides in the provision of a structure of this type which may be readily hung in position and which will maintain such position with a degree of firmness sufficient for the purpose, 20 but which may be removed whenever desired without the use of any tools whatever.

A further object of my invention resides in making this structure collapsible, so that it will require very little space when in its 25 collapsed position, but which may be moved to an operative position and be made to keep this position as long as desired.

The preferred embodiment of my invention is shown in the accompanying sheet of 30 drawings, in which similar characters of reference designate corresponding parts, and in which:

Figure 1 is a central vertical section of the foot portion of a bed, showing my invention attached and also in section.

Fig. 2 is a view in perspective of one of the supporting members used in the construction of my device showing the movable parts thereof in two positions, one being in 40 full lines and the other in broken lines.

Fig. 3 is an end view of the structure shown in Fig. 1 on a reduced scale, and,

Fig. 4 is a plan view of the structure shown in Fig. 3.

45 In the drawings, the foot frame of a well known type of bed is shown as comprising legs 1 and a U-shaped superstructure 2, this superstructure being braced by a cross rod 3 and tie rods 4, each shown as extending vertically between the cross piece 5 of the U-shaped member and the cross member 3.

In order that my attachment may be readily applied, I have provided a plurality of spaced hanger members 6, these hanger members being formed at their upper ends

to assume the shape of a hook 7 for embracing the portion 5 of the foot piece. Extending rearwardly from the rear side of each of these hanger members, I have also provided a plurality of ears 8 arranged in pairs and the two ears forming each pair being spaced from each other and disposed along opposite edges of the hangers 6, thus providing a space to receive the rods 4 as more clearly shown in Fig. 2. The opposite face of each of the hangers 6 is also provided with two sets of pierced ears 9 and 10, the former being provided to pivotally receive an outwardly extending bracket arm 11. These bracket arms are designed to be attached to the underside of a table or desk element shown at 12 and their pivotal connection is provided so that this desk element may be swung to assume either a horizontal or a vertical position.

In order that the desk element 12 may be securely locked in its horizontal position, I have provided a brace member for each hanger, these brace members being formed of levers 13 and 14, and being respectively attached to the hanger members and the bracket arms at 15 and 16. In addition, the opposite ends of each pair of levers are pivotally connected together as is shown at 17, thus providing brace members which may be made to assume the position shown in Fig. 1, whereby the desk is held in horizontal position, or they may be broken as shown in full lines in Fig. 2 prior to the lowering of the desk to make it assume a vertical position. In order to lock the levers 13 and 14 against accidental breaking, I have extended the end 18 of the lever 14 to a considerable distance beyond its pivot point and have provided this extension with 95 a lip 19 designed to overlie the top edge of the lever 13 after the manner shown in Figs. 1 and 2.

It will thus be apparent that I have provided an attachment which may be readily hung in position and moved to assume either an operative or a horizontal position or an inoperative or vertical position as may be desired. Further, this attachment remains in place with sufficient firmness to prevent 105 its accidental displacement, but yet it may be easily removed without the use of any tools whenever such removal is desired.

What I claim, is:

1. A writing desk attachment for a bed 110

- comprising spaced hanger members each provided with means at its top for attachment to the upper portion of the foot piece of a bed, a pair of rearwardly projecting ears spaced along opposite edges of the upper portion of each of said hangers, a pair of rearwardly projecting ears spaced along opposite edges of the lower portion of each of said hangers, the ears of each pair being spaced from each other to receive the rods forming a portion of the foot of the bed between them, an outwardly extending bracket arm pivoted to the upper end of each of said hangers, a table element attached to said arms, a brace member for each arm formed of a pair of levers pivoted together at one of their ends and pivotally connected at their other ends to said hanger and arm respectively, one end of one of said levers being extended beyond the first named pivotal connection, and a lip on the extended portion of such lever over-lying its complementary lever to limit the movement of said levers when they are pivoted together. 2
5. A writing desk attachment for a bed comprising spaced hanger members each formed of a single strap bent to hook shape at its upper end, a pair of integrally formed rearwardly projecting ears spaced along opposite edges of the upper portion of each of said hangers, a pair of integrally formed
10. spaced from each other to receive the rods forming a portion of the foot of the bed between them, an outwardly extending bracket arm pivoted to the upper end of each hanger, a table element attached to said arms, and a collapsible brace member operatively connected between each hanger and its respective bracket arm. 3
15. 2. A writing desk attachment for a bed comprising spaced hanger members each formed of a single strap bent to hook shape at its upper end, a pair of integrally formed rearwardly projecting ears spaced along opposite edges of the upper portion of each of said hangers, a pair of integrally formed
20. 3. In testimony whereof I affix my signature in presence of two witnesses. 34
- DAVID M. BEAIRD. 40
